UNITED STATES PATENT OFFICE.

ALBERT A. HUTCHINSON, OF WINCHESTER, MASSACHUSETTS.

HIDE-WORKING MACHINE.

No. 806,256.

Specification of Letters Patent.

Patented Dec. 5, 1905.

Application filed January 17, 1905. Serial No. 241,477.

To all whom it may concern:

Be it known that I, ALBERT A. HUTCHINSON, a citizen of the United States of America, and a resident of Winchester, in the county of 5 Middlesex and State of Massachusetts, have invented certain new and useful Improvements in Hide-Working Machines, of which the following is a specification.

This invention relates to machines for removing hair and superfluous flesh from hides, and particularly to that class of machines which are adapted to be used for either fleshing or unhauling, and has for its object the production of such a machine which may be 15 readily adapted for either purpose with but very slight adjustment in the mechanisms.

It is an improvement upon the inventions fully shown and described in Letters Patents No. 745,353, issued to me December 1, 1903, 20 and No. 762,415, issued to me June 14, 1904.

It consists in certain novel features of construction and arrangement of parts which will be readily understood by reference to the description of the drawings and to the claims to 25 be hereinafter given.

Of the drawings, Figure 1 represents a front elevation of the left end of a machine embodying this invention. Fig. 2 represents a front elevation of the right end of same. Fig. 3 represents an end elevation of the left end of same. Fig. 4 represents an end elevation of the right end of same. Fig. 5 represents a vertical section of the same on line 5-5 of Fig. 1. Fig. 6 represents a similar vertical 35 section with the apron in position to coöperate with the hide-working cylinders. Fig. 7 represents an enlarged vertical section of the hide-support with the feed-rolls and fleshing-cylinder in position to coöperate therewith. Fig. 8 represents a similar section of the hide-support with the feed-rolls and the unhauling-cylinder in position to coöperate therewith. Fig. 9 represents an end elevation of one of the feed-rolls. Fig. 10 represents a 40 section of one end of a feed-roll and its bearing. Fig. 11 represents an enlarged end elevation of the driving-gear-supporting member and the pivoted gear-supporting frame for operating the hide-supporting apron, the 45 driving-gears being shown in dotted lines and the pivoted frame being shown in position for the hide-support to coöperate with the knife-cylinder. Fig. 12 represents an end elevation of the apron-roll-supporting frame showing its connections with the weighted 50 lever for normally-limiting the movement of 55

said frame and permitting its yielding under abnormal tension. Fig. 13 represents a vertical section of the knife-cylinder-supporting frames, showing a knife-grinder in position 60 upon its supporting-bar; and Fig. 14 represents an elevation of one end of the bar for supporting the knife-grinder.

Similar characters designate like parts throughout the several figures of the drawings. 65

To support the working parts of the machine, a main frame is preferably provided made up of end frames 10 10 and tie-girths 11 11. To the left end frame is secured a bracket 12, supporting a frame 13, from which projects a stud 14, secured thereto. On the stud 14 is mounted, so as to be freely revolute thereon, a sleeve 15, provided at one end with pinion-teeth 16 and having secured to the opposite or outer end a double pulley 17 70 and 18. The pulleys 17 18 are of different diameters and are intended to coöperate at different times, by means of a belt 19, with pulleys 20 and 21, secured, respectively, to the shafts 22 and 23 of the unhauling-knife cylinder 80 24 and the fleshing-cylinder 25.

In Fig. 1 the belt 19 is shown as connecting the pulleys 17 and 20, and in this position the unhauling-knife cylinder is in position to coöperate with the hide-supporting apron 26 85 when said hide-supporting apron 26, with a hide thereon, is moved into position by the operator to coact with said knife-cylinder.

The hide-supporting apron 26 is mounted upon two apron-rolls 27 28, the upper of 90 which is provided with trunnions 29 at either end provided with bearings in the pivoted frame 30, pivoted at 31 to the outside of the side frame 10. The trunnion 29 at the left of the machine is provided with a gear 32, 95 by which motion is imparted to said apron-roll 27 in either direction, according to the position in which the hide-supporting apron 26 may be. Intermediate the end of the roll 27 and the side frames 10 each trunnion 29 is provided with an arm 33, the lower end of which is bifurcated at 34 and is provided with an adjustable block 35, forming a bearing for the trunnion 36 of the lower apron-roll 28. This block 35 may be adjusted, by means of 100 the screw 37, to vary the tension of the apron, as desired, a spring 38, bearing against the inner end of said block 35 to keep the apron that at all times. Between each arm 33 and an end of the apron-roll 27 is interposed the 110 swinging members 39, carrying a slideable block 40 for supporting the bed-roll 41. The

block 40 is provided with the usual spring-tension device 42. The member 39 is provided with a projection 43, provided with a clamping-bolt 44, which coöperates with a slot 45 in a member 46, projecting toward the front of the machine from the swinging arm 33. By means of this device the bed-roll 41 may be swung into any desired position around the axis of the trunnion 29 and clamped 10 by means of the bolt 44. To prevent the bolt 44 from slipping in the slot 45 under extraordinary strain, the member 46 is provided with an ear 47, into which is threaded a bolt 48, bearing against the upper end of the projection 43, thereby holding the bed-roll 41 rigidly in any position in which it may be adjusted and clamped.

The gear 32 for driving the upper apron-roll 27 meshes with an intermediate gear 49, 20 which in turn meshes with a gear 50, both of said gears 49 50 being loosely mounted upon studs 51 52, projecting from the pivoted frame 30. At 53 a link 54 is pivoted to said frame 30, the opposite end of said link being connected at 55 to a rocker-arm 56, secured to the rocker-shaft 57, said shaft being operated by means of a treadle 58 or in any other well-known manner.

To the frame 13 on a stud 59 is loosely 30 mounted a gear 60, which meshes with the gear 52 on the pivoted frame 30 when the hide-supporting apron is inoperative position. The gear 60 is operated by means of a gear 61, which also operates a gear 62, causing it to move in the same direction as the gear 60. The gear 61 is mounted upon the hub of a gear 63, which meshes with the gear 16 and is driven thereby. The gears 62 63 are mounted, respectively, upon studs 64 65, projecting 40 from the frame 13.

The shaft 22 of the unhairing-cylinder 24 has secured to its opposite end a driving-pulley 66, by which said knife-cylinder may be revolved at any desired speed. The motion imparted to the knife-cylinder is transmitted through the pulley 20, belt 19, and pulley 17 to the gearing mounted upon the studs projecting from the frame 13, so that when the unhairing-cylinder is in operation these gears 45 are continually revolving. When the frame 30 is in the position shown in Fig. 3, with the hide-supporting apron 26 removed from the unhairing-cylinder, the gear 50 of said frame meshes with the gear 60 on the frame 13 and 50 causes motion to be imparted to said apron 26 to move it in the direction indicated by the arrow on Fig. 5—*i. e.*, in a direction to feed a hide into position to be operated upon. As soon as the hide has been fed in sufficiently, 55 far upon the apron 26 to be in position to be operated upon the operator places his foot upon the treadle 58, depressing the same, and thereby causing the rocker-arm 56 to straighten the toggle formed by it and the 60 link 54. This operation causes the frame 30

to be moved about its pivot 31 and moves the hide-supporting apron 26 into the position shown in Fig. 8, at which time the gear 49 will mesh with the gear 62, and thereby cause the gear 32 to rotate in the opposite direction, 70 thereby moving the apron 26 in a direction to feed the hide supported thereon outwardly to cause the hair to be removed from the hide in a well-known manner. When the gear 49 is in mesh with the gear 62, the gear 50 is out 75 of mesh with the gear 60, as shown in Fig. 11. When the apron 26 has been moved by the depression of the treadle 58 into position to coöperate with one of the knife-cylinders, that portion of the apron which is supported by 80 the apron-roll 27 with the hide thereon will coöperate with the feed-rolls 67 and 68, mounted in bearings in the boxes 69 70, slidably mounted in the frames 71 72, said frames being pivoted at 73 and adjustable about said pivot independently of each other and clamped in any desired adjusted position by means of the clamping-bolts 74, coöperating with the slot 75 in the end frame 10.

Each of the frames 71 72 is provided with 90 a spring-tension device 76 of usual construction. The trunnions 77 of said feed-rolls are each provided with a gear 78, which is adapted to coöperate with a gear 79 on a trunnion 29 of the upper apron-roll 27 when the apron 26 95 is in position to coöperate with a knife-cylinder. When the gears 78 79 are in mesh, the feed-rolls 67 68 will coöperate with the apron 26, supported by the roll 27, to positively feed the hide outwardly against the tension 100 of the knife-cylinder 24 or 25, acting thereon to remove the hair or flesh therefrom.

The pivoted frame 30 at either end of the machine is connected, by means of a link 80, to the shorter arm 81 of a bell-crank lever 82, 105 pivoted at 83 to the side frame 10 of the machine. The longer arm of said lever 82 is provided with a weight 84, adjustable lengthwise thereof. The lever 81 82 is so constructed that when the pivoted frame 30 is 110 moved to the rear to carry the apron 26 into position to coöperate with the knife-cylinders the longer arm 82, with the weight 84 thereon, will be carried beyond a line perpendicular to the axis of the pivot 83 and will 115 be held in such position by means of the operator retaining his foot upon the treadle 58, he being assisted in this operation by means of the link 54, which at its pivotal connection 55 with the rocker-arm 56 is provided 120 with rolls 85, which coöperate with the cam-plate 86, pivoted at 87 to the end frames 10. When the apron is in position to coöperate with the knife-cylinder, the link 54 will be in a nearly vertical position, with the rolls 85 125 resting upon a nearly horizontal portion of said cam 86, so that all of the strain in supporting the various weights of the elements moved by the treadle is taken from the operator. As soon as the operator removes his 130

foot from the treadle the weight 84 by gravity will move into a position beneath the pivot 83, thereby moving the pivoted frame 30 about its pivot and causing the link or strut 54 to be further inclined, and thereby permit the weight of said frames 30, the apron-rolls, and other members supported thereby to cause all of the various elements moved by the treadle to be returned to their normal position, as shown in the drawings. As the rolls 85 return to their lower position in the cam-plate 86, they contact with a leather buffer 88 in the lower end thereof to prevent unnecessary jar of the various elements.

15 The cam-plate 86 is adjustable about its pivot 87 by means of the slot 89 and clamping-bolt 90. The frame 30 is provided with a projection 91, which engages with a projection 92 upon the frame 10 to limit the inward movement of the frame 30 to prevent injury to the hides or apron by too severe a contact with the knife-cylinders 24 25. The shafts 22 23 of the knife-cylinders 24 25 are mounted in bearings in side plates 93, pivoted at 94 to the inside of the main side plates 10 of the machine. The side plates 93 are each provided with a slot 95, concentric to the pivot 94, and clamping-bolts 96, secured to the frame 10, coöperate with this slot to clamp said plates 30 in position for either knife-cylinders 24 25 to coöperate with the apron 26. The outer end of the shaft 94 has secured thereto a two-armed member 97, each arm of which is provided with an adjusting-screw 98, adapted to engage with a lug 99, projecting from the side frame 10. The adjusting-screws 98 are adjusted so that when the side plates 93, with the knife-cylinders 24 25 therein, are moved about the pivot 94 each will be stopped in its proper position to coöperate with the apron at a predetermined point.

45 The unhairing-cylinder 24 is mounted in the plates 93 at a greater distance from the pivot 94 than the fleshing-cylinder 25, and the adjustable stops 98 are so arranged that when the unhairing-cylinder is in position to coöperate with the hide it will be in a lower position than the position assumed by the fleshing-cylinder when it has been moved into position to coöperate with the hide. The object of this is to so locate the fleshing-cylinder 25 relative to the pivot 94 and the stops 98 99 that when moved into position to coöperate with the apron it will always assume a position practically opposite the bed-roll 41, as indicated in Figs. 6 and 7, while at the same time it is desirable that the unhairing-cylinder 24 should be so located relative to the pivot 94 and stops 98 99 that when it is moved 55 into position to coöperate with the apron it will assume a position intermediate said bed-roll 41 and the apron-roll 28, thereby securing a more yielding surface than if it came into contact with the apron at a point where it passed over the bed-roll 41. In the previous ma-

chines referred to this object was accomplished by withdrawing the bed-roll from contact with the rear of the apron, which made extra labor for the operator, and this is entirely obviated by the present invention, as is obvious.

70 The shaft 23 of the knife-cylinder 25 is provided on its right-hand end with a driving-pulley 100, from which power is transmitted from any suitable counter-shaft to drive said knife-cylinder. When the knife-cylinder 25 is in operation, the belt 19 is removed from the pulleys 20 and 17 and placed upon the pulleys 18 and 21, and motion is transmitted thereby from the pulley 21 to the pulley 18 to drive the apron-gearing, as heretofore described.

75 The side plates 93 are each provided with inwardly-projecting lugs 101, to which is secured the grinder-bar 102, provided with 85 projecting guides 103, which coact with the grinder 105, as shown in Fig. 13, thereby permitting the knife-grinder to be reciprocated back and forth along the bar 102 for the purpose of sharpening the knives of the 90 knife-cylinders when desired. The bar 102 is secured to the lugs 101 by bolts 106, and said bar may be transferred from one side of said lug to the other, the two faces of said lug being of such an inclination that when 95 the bar 102 is secured to either face and the knife-grinder is placed thereon said grinder will be radial to either of the knife-cylinders with which it may be coöperating. The guides 103 of the grinder-bar 102 are cut 100 away at 103* at either end thereof to permit the removal of the grinder 105 when not to be used and the replacing thereof when it is desired to sharpen the knives of the cylinders 24 25.

105 When the grinder 105 is not in use, a barrier 107 is inserted between the shaft 94 and the grinder-bar 102, being supported thereon by means of hooked supports 108. This barrier 107 has no special use when the unhairing-knife cylinder 24 is in operation, but when the fleshing-cylinder is in operation, as shown in Figs. 6 and 7, it is desirable that the flesh removed from the hide should not clog up the unhairing-knife cylinder 24, which 110 at that time is almost immediately below the knife-cylinder 25 and is in a position to receive the most of the refuse removed from the hides in the operation of said cylinder. To prevent this, a metallic plate or hood 109 115 is hooked into the barrier 107, said plate being supported thereby and being curved, so that it will cover the upper portion of the unhairing-cylinder 24 and prevent the flesh and other waste removed from the hide from coming in contact therewith. This plate 109 is removed when the unhairing-cylinder 24 is 120 in operation.

125 When the machine is in operation, it is convenient for the operator to have some support 130

for his hands when not being used in manipulating the hides. For this purpose a rod 110 is provided supported by arms 111, pivoted to the studs 73.

5 In front of the apron-roll 28 and at a lower level supported on angle-irons 112 is a shelf 113, inclined downwardly to the rear. The rear end of said shelf is provided with a back-stop 114, and said shelf is provided with a drain-hole 115. The purpose of this shelf is to permit the hide being operated upon as it drops from the hide-support 26 to fold itself upon this shelf in a position readily accessible to the operator when he desires to turn it and place the other half upon the apron to finish the operation. While the hide remains upon the shelf, any liquid which may remain thereon will drain through the openings 115. The provision of this shelf dispenses with considerable labor on the part of the operator and much unnecessary lifting.

At 116 an eyebolt 117 is pivoted to the lower end of the swinging arms 33. The threaded end of the eyebolt 117 passes through 25 a member 118, on either side of which said eyebolt is provided with a nut 119. The member 118 is pivoted at 120 to a short arm 121 of a lever 122, pivoted at 123, the longer arm of said lever being provided with a 30 weight 124, adjustable lengthwise of said longer arm. The longer arm of the lever 122 normally rests in a forked support 125, secured to the rear tie-girth 11.

Under normal conditions the eyebolt 117 35 acts as a radius-arm, so that when the operator's foot is placed upon the treadle and depressed for the purpose of moving the apron 26 into position to coöperate with the knife-cylinders the eyebolt or radius-arm 117 will 40 prevent the lower end of the arms 33 from moving toward the rear, thereby swinging said arms 33 about the trunnions 29 as said trunnions, with their apron-roll 27, are moved toward the rear of the machine into the position shown in Figs. 6 and 7. In this position when the hide is being operated upon by means of a knife-cylinder the hide will hang downwardly from the point where it is in contact with said knife-cylinder, as shown in 45 Fig. 7, and will not come in contact with the apron 26 until it reaches that point where the operation upon the hide by the knife-cylinder is performed. This inclination of the apron so that the hide does not contact therewith 50 during its operation until it reaches a point where the knife-cylinder coacts therewith is a very important feature of this invention, as by such a construction and arrangement of parts the hide is much more readily spread 55 during the operation thereon of the knife-cylinders than would be the case if it rested upon the apron previous to reaching the point of operation. Heretofore in machines of this class where an apron is used the hide is supported by the apron for some little distance 60

before it reaches the knife-cylinder and usually hugs the apron so closely that the proper spreading of the hide is seriously interfered with, and as a consequence oftentimes the hide is injured by the knives of the knife-cylinders. These objections are entirely obviated by the present invention.

Should any extra thickness of the hide pass between the apron and the knife-cylinder which would be liable to be injured by the knives of the knife-cylinder, the arms 33 will swing about the trunnions 29, thereby forcing the arm 121 of the lever 122 downwardly and slightly lifting the weight 124 in its forked support 125. As soon as the extra thickness is passed, the weight 124 will return the various parts to their normal position. This device permits delicate hides to be operated upon without injury.

The feed-rolls 67 68 are constructed of an inner metallic core 126, provided with a plurality of radial ribs 127. Between the ribs 127 are secured filling-pieces of wood 128, which combine to form a cylinder having a non-metallic periphery. These filling-pieces 90 128 are secured to the inner core by means of the screws or other fastening devices 129. The outer periphery of the feed-rolls is formed of woven fabric, felt, or other similar material 130, spirally wound thereon and secured 95 to the filling-in pieces by means of fastening devices 131. Each end of the core 126 is provided with a socket 132, capable of receiving a cylindrical trunnion 77, which is secured therein by means of the set-screw 133. A 100 feed-roll of this construction is very efficient in its operation, and when worn or damaged the filling-in pieces 128 and the outer periphery 130 may be readily replaced at slight expense.

By means of the socket 132 and the trunnion 77, secured therein by means of the set-screw 133, the feed-rolls may be readily removed from the machine by moving the trunnions 77 outwardly through their bearings in 110 the direction of the arrow in Fig. 10 sufficiently far so that the inner end of the trunnion will clear the outer end of the core 126.

It is believed that the operation of this invention will be thoroughly understood by the foregoing description.

Having thus described my invention, I claim—

1. The combination with a pair of separated rolls, of an apron mounted upon said rolls, a pivoted frame, a pair of independently-driven knife-cylinders mounted in said frame at different distances from said pivot, and means whereby said frame may be moved about its pivot to bring either of said knife-cylinders 120 into position to coöperate with said apron at different points thereon intermediate said rolls.

2. The combination with a pair of separated rolls, of an apron mounted upon said rolls, a 130

bed-roll located between said rolls beneath said apron, a pivoted frame, a pair of independently-driven knife-cylinders at different distances from the pivot of said frame, and 5 means whereby one of said cylinders may be moved into position to coöperate with said bed-roll or the other may be moved into position to coöperate with said apron at a point intermediate said bed-roll and an apron-roll.

10 3. The combination with a knife-cylinder, of a pivoted frame, a pair of apron-rolls both having bearings in said frame at some distance from the pivot thereof, an apron mounted on said rolls, a bed-roll also carried by said frame, 15 and means for moving said frame to cause said apron to coöperate with said knife-cylinder at a point intermediate the bed-roll and an apron-roll.

4. The combination with a knife-cylinder, 20 of a frame pivoted to the framework of the machine, a hide-support pivoted to the free end of said pivoted frame, means for moving said pivoted frame into position for the hide-support to coöperate with said knife-cylinder, 25 a weighted lever, and a link interposed between said lever and said hide-support.

5. The combination with a knife-cylinder, 30 of a frame pivoted to the framework of the machine, a hide-support pivoted to the free end of said pivoted frame, means for moving said pivoted frame into position for the hide-support to coöperate with said knife-cylinder, a weighted lever, a link interposed between said lever and said hide-support, and means 35 for adjusting said link.

6. The combination with a knife-cylinder, 40 of a pivoted rocker-frame, arms pivoted to said rocker-frame, a hide-support mounted on said arms, means for moving said frames about their pivots to cause said hide-support to coöperate with said knife-cylinder, and means including a weighted lever for limiting the movement of said arms about its pivot.

7. The combination with a knife-cylinder, 45 of a pivoted rocker-frame, a hide-support pivoted to said rocker-frame, means for moving said rocker-frame about its pivot, a weighted lever, and a link connecting said lever and hide-support.

50 8. The combination with a knife-cylinder, of a hide-supporting apron, and means for moving said apron into an inclined position engaging said knife-cylinder with the upper portion of said hide-support farthest to the 55 rear and higher than said knife-cylinder while the lower portion is lower than said cylinder and nearer the front of the machine.

9. The combination of two side plates, two 60 knife-cylinders mounted in said plates, a lug on each side plate, and a guide-bar adapted to be secured to either side of said lugs to support a grinder in position to coöperate with either cylinder.

10. The combination of two side plates, two 65 knife-cylinders mounted in said plates, a bar-

rier connecting said plates in the rear of one of said cylinders, and a hood secured thereto for the other cylinder.

11. The combination of two side plates, two 70 knife-cylinders mounted in said plates, a barrier connecting said plates in the rear of one of said cylinders, and a detachable hood secured thereto for the other cylinder.

12. The combination of two side plates, two 75 knife-cylinders mounted in said plates, a barrier connecting said plates in the rear of one of said cylinders, hooks on said barrier, and a hood for the other cylinder secured thereto.

13. The combination of a knife-cylinder, a 80 revoluble hide-support, a driving-gear therefor, gearing meshing therewith when said hide-support is removed from said cylinder to drive said support in one direction, and gearing meshing with said driving-gear to move the hide-support in the opposite direction 85 when said support is coöperating with said knife-cylinder.

14. The combination of a knife-cylinder, a 90 revoluble hide-support, a pivoted supporting-frame therefor, a driving-gear for said hide-support, two pinions on said frame for driving said gear, two driving-gears moving in the same direction mounted on a bracket, and means for moving said frame about its pivot to cause one of said frame-pinions to be moved 95 out of mesh with one of said bracket-gears and into engagement with the other.

15. The combination of a knife-cylinder, a 100 hide-supporting apron, means for moving said apron toward the front of the machine when the hide is being operated upon, and a shelf between the front of the machine and said apron adapted to receive and hold the hides after being operated upon.

16. The combination of a knife-cylinder, a 105 hide-supporting apron, means for moving said apron toward the front of the machine when the hide is being operated upon, a shelf in front of said apron adapted to receive the 110 hides after being operated upon, and means for draining said shelf.

17. The combination of a knife-cylinder, a 115 hide-supporting apron, means for moving said apron toward the front of the machine when the hide is being operated upon, a shelf in front of said apron adapted to receive the 120 hides after being operated upon, means for draining said shelf, a weighted lever, a nut pivoted to the free end thereof, a hide-support, and a threaded shank coöperating with said nut and pivoted to said hide-support.

18. The combination with a knife-cylinder, 125 of a feed-roll above said cylinder, an apron downwardly and backwardly inclined toward said knife-cylinder, and means whereby said apron may be brought into position to coöperate with said knife-cylinder and feed-roll with said apron downwardly and forwardly inclined from said knife-cylinder.

19. The combination with a knife-cylinder, 130

- of a pair of levers, pivots therefor, a hide-support pivoted to the free ends of said levers, a bed-roll, and supports for said bed-roll hung on said pivots.
5. 20. The combination with a knife-cylinder, of a pair of levers, pivots therefor, a hide-support pivoted to the free ends of said levers, a bed-roll, supports for said bed-roll hung on said pivots, and means for adjusting the position of said supports about said pivots.
21. The combination with a knife-cylinder, of a pair of levers, pivots therefor, an apron-roll pivoted to the free end thereof, arms hung on said pivots, an apron-roll in bearings in the free end of said arms, and an apron on said rolls.
22. The combination with a knife-cylinder, of a pair of levers, pivots therefor, an apron-roll pivoted to the free end thereof, arms hung on said pivots, an apron-roll in bearings in the free end of said arms, an apron on said rolls, and means for regulating the movement of said arms about said pivots.
23. The combination with a knife-cylinder, of a pair of levers, pivots therefor, an apron-roll pivoted to the free end thereof, arms hung on said pivots, a second apron-roll supported thereby, an apron on said rolls, a bed-roll beneath said apron, and supports therefor hung on said pivots.
24. The combination with a knife-cylinder, of a pair of levers, pivots therefor, an apron-roll pivoted to the free end thereof, arms hung on said pivots, a second apron-roll supported thereby, an apron on said rolls, a bed-roll beneath said apron, supports therefor hung on said pivots, and means for adjusting said supports relative to said arms.
25. The combination with a knife-cylinder,
- of a pivoted frame, a hide-support pivoted to the free end thereof, means for moving said frame to cause said support to coöperate with said cylinder, and means for reversing the inclination of said support during said movement.
- 45 26. The combination with a knife-cylinder, of a pivoted frame, a hide-support pivoted to the free end thereof, means for moving said frame to cause said support to coöperate with said cylinder, means for reversing the inclination of said support during said movement, and means secured to said hide-support providing for a yielding movement about its pivots under abnormal strain.
- 50 27. The combination with a knife-cylinder, of a pivoted frame, a hide-support pivoted to the free end thereof, means for moving said frame to cause said support to coöperate with said cylinder, means for reversing the inclination of said support during said movement, and means including a weight secured to said hide-support providing for a yielding movement about its pivots under abnormal strain.
- 55 28. The combination with a knife-cylinder, of a feed-roll located above said cylinder, a pair 65 of apron-rolls, a hide-supporting apron upon said rolls, and means for moving said apron into engagement with said cylinder and feed-roll with that portion of the apron extending from the cylinder to the lower apron-roll inclined therefrom.
- 60 Signed by me at Boston, Massachusetts, this 9th day of January, 1905.
- ALBERT A. HUTCHINSON.
